GUARD FOR PRESSES

Filed June 7, 1929

INVENTOR.
Clinton E. Marshall
BY
Howard E. Thompson
ATTORNEY

UNITED STATES PATENT OFFICE

CLINTON E. MARSHALL, OF BROOKLYN, NEW YORK

GUARD FOR PRESSES

Application filed June 7, 1929. Serial No. 369,102.

This invention relates to presses of various kinds and classes and particularly to what are known as foot presses, and to the provision of a guard in operative engagement with the plunger of the press whereby the guard element may be moved with respect to the dies to forcefully remove a finger or hand from the path of the dies to prevent injury thereto; and the object of the invention is to provide a guard of the class and for the purpose specified in the form of an attachment which may be quickly and easily applied to and coupled with presses of conventional form; a further object being to provide a guard attachment of the class specified which is so constructed as to permit the adjustment of the parts thereof to adapt the same to many uses or to different kinds and classes of dies used in the presses; and with these and other objects in view, the invention consists in a guard attachment of the class and for the purpose specified which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:—

Fig. 1 is a front view of a part of a foot press showing one form of attachment mounted in connection therewith and indicating the method of its use.

Fig. 2 is a side view of the structure shown in Fig. 1.

Fig. 3 is a view similar to Fig. 1 but showing a modification.

Fig. 4 is a side view of the structure shown in Fig. 3, and,

Fig. 5 is a side view of a press similar to that shown in Figs. 1 and 2, illustrating another arrangement of attachment thereon.

My invention relates to guard attachments for presses of various kinds and classes, and for the purpose of illustrating one use of my invention, I have diagrammatically shown in the accompanying drawings, portions of a foot press of conventional form and like ref-

erences will designate like parts of the press in the several figures. A part of the body portion or frame of the press is indicated at 10 in the several figures, and 11 represents a vertically movable plunger, 12 the plunger die, 13 the bed or table of the press upon which is the lower or stationary die block 14, it being understood at this time that the dies 12 and 14 may be of any desired form and construction.

In Figs. 1 and 2 of the drawings, I have shown one form of attachment which consists in a bar or strip 15 secured to the upper end portion of the plunger 11 by screws or other means 16 and projecting at one side of the press, the free end portion having a vertical aperture to receive a connecting rod or operating arm 17, the upper end of which is adjustably fixed to the bar 15 by a set screw or other means 18. A lever 19 is pivotally supported in connection with the frame 10 on a pivot screw 20, a spacing member 21 being preferably employed inwardly of the lever so as to arrange the same in proper position with respect to the frame and also to clear the outer face of the plunger 11, the short end 19a of the lever having a vertical aperture to receive the upper end of a guard arm 22 which is adjustably supported with respect to the end 19a by means of a set screw 23.

The long arm 19b of the lever 19 projects outwardly at the side of the press and the lower offset portion 17a of the connecting rod 17 rests upon and cooperates with said end of the lever to control the operation of the guard arm 22. A spring 24 is preferably coupled with the end 19b of the lever and with the frame 10 to hold the end 19b of the lever in engagement with the rod 17 at all times.

A guard arm 22 as seen from the front of the machine, is offset outwardly, downwardly and inwardly and is arranged to move over the upper face of the die block 14, and the end portion of said arm has an inwardly directed extension 22a, note Fig. 2, which is arranged to pass directly in front of but clearing the die 12. The normal position of the parts of the attachment is shown in full lines in Fig. 1 when the plunger is in raised

position, and in dotted lines, I have illustrated the position assumed by the attachment after the descent of the plunger, it being noted that the lower end portion of the arm 22 is passed beyond the vertical center of the die 12 so as to remove the finger of a hand which is indicated in dotted lines at 25 should the same be in the path of said arm.

10 This type of attachment is designed primarily for use in stamping or forming work-pieces wherein it is customary and necessary to leave one finger of the hand upon the die 14 to support the workpiece in proper 15 position, and my improved guard device will insure the removal of the finger of a hand, preventing injury thereto, should the finger have been misplaced in the path of the guard or the plunger die. At this time, it will be 20 understood that the lower end portion of the arm 22 may be bent or fashioned to suit any type, kind or class of dies and work-pieces requiring support by one or more fingers of the hand during the press operation.

25 In many uses of presses of the class under consideration, all that will be necessary will be to move a guard arm transversely with respect to the front of the two dies employed in the machine, so as to remove a finger or 30 hand should it accidentally be left in the path of the dies, and especially the plunger die.

In Figs. 3 and 4 of the drawings, I have shown a form of construction suitable for this purpose. In this construction, I employ a 35 bar 26 similar to the bar 15 and which is secured to the plunger 11, and to the outer end of which is adjustably secured a connecting rod 27 operating upon the outer end of a lever 28 pivoted to the frame 10 as seen at 40 29, a spring 30 being arranged between the outer end of the lever and the bar 26 to support the lever 28 constantly in engagement with the connecting rod 27.

45 A guard arm 31 is adjustably secured to the inner end of the lever 28 and extends outwardly, downwardly and inwardly as seen in Fig. 4 of the drawings, the arm normally assuming the position shown in Fig. 3 of the drawings and being adapted to 50 be moved to the right across the vertical center of the dies 12 and 14 in the same manner as the movement of the arm 22 so as to remove a finger or hand which may be arranged in the path of movement of said 55 guard arm, it being seen that the arm 31 extends below the die 14 instead of working over the upper surface of said die as in the construction shown in Figs. 1 and 2 of the drawings.

60 In Fig. 5 of the drawings, I have shown another modification which consists primarily in arranging the lever and guard arm at one side of the machine rather than at the front thereof so as to control and insure the 65 removal of a finger or hand when it is essen-

tial to feed the work into the dies from one side of the machine rather than at the front of the machine. In this construction, a connecting rod 32 is employed and coupled with a bar similar to the bar 15 or 26 and is offset 70 backwardly and downwardly at one side of the machine to engage the backwardly directed end of a lever 33 pivoted to the frame 10 as seen at 34, a spring 35 being employed to support the lever 33 in engagement with 75 the connecting rod 32; and a guard arm 36 is adjustably supported in connection with the forward end of the lever and extends backwardly and downwardly, the lower end of said arm being normally arranged rearwardly 80 of the lower die 14 to permit the free feeding of a workpiece into the die from the side of the press. In the descent of the plunger, the guard arm 36 will move forwardly and across the vertical central path 85 of the plunger die 12 at the side thereof.

From the foregoing, it will be apparent that in the several forms of construction shown, three distinct elements are employed in the attachment, namely the lever to one end of which is adjustably secured the guard arm, and the connecting rod operably engaging the other end of the lever and adjustably coupled with the plunger so that the downward movement of the plunger will impart predetermined movement to the guard arm with respect to the dies supported in the press to insure the removal of a finger or hand to prevent accident or injury thereto.

It will also be understood that my improved attachment in no way interferes with the quick and successful operation of the machine and by virtue of the simplicity of the construction, the attachment may be coupled with and incorporated as a part of the press at a nominal cost and further by virtue of the adjustments provided for the connecting rod and guard arm, the same may be adapted to machines of different kinds and classes and to cooperate with dies of different shapes and forms.

It will be understood that the guard arm of the several attachments shown will operate to engage and remove a finger or hand prior to the complete descent of the plunger, and will be so timed as to insure the removal of a finger or hand before the same can be caught between the plunger die and stationary die.

At this time, it will also be apparent that my invention is not necessarily limited to any particular shape or form of the connecting rod, and guard arm employed, the same being constructed of rod-like material preferably of a texture which will permit the bending 125 and shaping thereof as well as the rebending and reshaping without danger of breaking the same. While I have shown certain uses of my invention as well as specific structural details of the several parts of the attachment, 130

it will be understood that I am not necessarily limited in these respects and various other changes in and modifications of the construction herein shown and described may be made within the scope of the appended claims without departing from the spirit of my invention or sacrificing its advantages.

Having fully described my invention, what I claim as new and desire to secure by Letters Patent, is:—

1. A guard attachment for presses comprising a part adapted to be coupled with the plunger of the press, a lever pivoted to the lower end of the frame of the press above the bed plate thereof, a guard arm adjustably supported in connection with one end of said lever and having an offset portion arranged to move transversely with respect to and adjacent the front of the plunger die of the press, an operating rod adjustably coupled with said part and extending from said part to said lever and bearing upon the other end of said lever to transmit movement to said guard arm in the descent of the plunger, and tensional means coupled with said frame and with the last named end of said lever for maintaining said end of the lever in constant engagement with said rod.

2. A guard attachment for presses comprising a part adapted to be coupled with the plunger of the press, a lever pivoted to the lower end of the frame of the press above the bed plate thereof, a guard arm adjustably supported in connection with one end of said lever and having an offset portion arranged to move transversely with respect to and adjacent the front of the plunger die of the press, an operating rod adjustably coupled with said part and extending from said part to said lever and bearing upon the other end of said lever to transmit movement to said guard arm in the descent of the plunger, tensional means coupled with said frame and with the last named end of said lever for maintaining said end of the lever in constant engagement with said rod, and the lower end portion of said rod being offset to dispose the end thereof engaging said lever at an inclination thereto when the plunger of the press is in raised position.

3. A guard attachment for presses comprising two independent and cooperating units, one of said units being supported in connection with the plunger of the press and the other in connection with the frame of the press adjacent the lower end of the plunger, said first named unit comprising a bar attached to the plunger and projecting at one side of the press, and a rod adjustably supported in connection with said bar and extending downwardly, another unit comprising a lever pivotally supported to the frame, said lever having a long end portion and a relatively short end portion, a guard arm adjustably supported in connection with the

short end portion of said lever and arranged to move transversely with respect to the plunger die adjacent the die plate of the press and the lower end portion of said rod abutting the long end of said lever, and tensional means coupled with the long end of said lever for maintaining the same in constant engagement with the lower end of said rod whereby in the descent of said plunger, said guard arm will be moved transversely of the front of the plunger die of the press.

4. A guard attachment for presses comprising two independent and cooperating units, one of said units being supported in connection with the plunger of the press and the other in connection with the frame of the press adjacent the lower end of the plunger, said first named unit comprising a bar attached to the plunger and projecting at one side of the press, and a rod adjustably supported in connection with said bar and extending downwardly, another unit comprising a lever pivotally supported to the frame, said lever having a long end portion and a relatively short end portion, a guard arm adjustably supported in connection with the short end portion of said lever and arranged to move transversely with respect to the plunger die adjacent the die plate of the press and the lower end portion of said rod abutting the long end of said lever, tensional means coupled with the long end of said lever for maintaining the same in constant engagement with the lower end of said rod whereby in the descent of said plunger, said guard arm will be moved transversely of the front of the plunger die of the press.

In testimony that I claim the foregoing as my invention I have signed my name this 18th day of May, 1929.
